(57) **CLAIM**

The ornamental design for a light fixture, as shown and described.

DESCRIPTION

This application is related to commonly assigned, concurrently filed application Ser. No. 29/252,116, the disclosure of which is hereby incorporated by reference herein. All the material from the copending application Ser. No. 29/252, 161, which is essential to the claimed design, is included in this application. It is understood that any material in the copending application, which is not present in this application, forms no part of the claimed design.

FIG. 1 is an isometric view of the first embodiment of the light fixture of the present invention;

FIG. 2 is a front elevation view thereof;

FIG. 3 is a right side elevation view thereof;

FIG. 4 is a rear elevation view thereof;

FIG. 5 is a left side elevation view thereof;

FIG. 6 is a top plan view thereof;

FIG. 7 is a bottom plan view thereof;

FIG. 8 is an isometric view of a second embodiment; and,

FIG. 9 is an isometric view of a third embodiment.

The broken line showing is included for the purpose of illustration only and forms no part of the claimed design.
